F. W. ROBINSON,
GAP CLOSING ATTACHMENT FOR KNITTING MACHINES.
APPLICATION FILED AUG. 7, 1918.

1,357,252.

Patented Nov. 2, 1920.

UNITED STATES PATENT OFFICE.

FRANK W. ROBINSON, OF READING, PENNSYLVANIA, ASSIGNOR TO THE NOLDE & HORST CO., OF READING, PENNSYLVANIA, A CORPORATION OF PENNSYLVANIA.

GAP-CLOSING ATTACHMENT FOR KNITTING-MACHINES.

1,357,252.

Specification of Letters Patent.

Patented Nov. 2, 1920.

Application filed August 7, 1918. Serial No. 248,711.

To all whom it may concern:

Be it known that I, FRANK W. ROBINSON, a citizen of the United States, residing at Reading, in the county of Berks and State 5 of Pennsylvania, have invented certain new and useful Improvements in Gap-Closing Attachments for Knitting-Machines, of which the following is a specification.

My invention relates particularly to knitting machines employing a latch guard ring having a gap for receiving the movable yarn-guide members ordinarily employed; and its consists in improved means for automatically closing such gap so as to positively avoid the danger of needle breakage 10 incident to unintended swinging or "flirting" of the latches. The invention is fully described in connection with the accompanying drawing, and the novel features are particularly defined in the subjoined claims.

Figure 1 is a plan view showing my invention applied as an attachment to an ordinary form of latch guard ring; one only of the series of coöperating yarn guides employed being shown.

Fig. 2 is a cross-sectional view on the line 2—2 of Fig. 1 looking in the direction of the arrow; the gap-closing bar being shown in retracted position, but its gap-closing 15 position being also indicated by dotted lines.

Fig. 3 is a sectional view on the line 3—3 of Figs. 1 and 2; the gap-closing bar being represented as swung into the gap.

The latch ring A is shown in well known 20 form, with a gap C in its inner circle extending between parallel arms C¹ C² which latter carry a series of automatically operated members, as B, mounted upon a pivot pin C³ and having their inner ends, commonly formed as thread carriers, adapted to be lowered into said gaps. Only one of these pivotally movable members B is indicated, the number employed depending 25 commonly upon the number of threads for which provision is made; and there is no showing of the cam-controlled operating means employed for moving the respective numbers into and out of operating position, excepting the single contacting lever indicated at F, inasmuch as such means are well known and readily adapted to automatically effect the required movements.

The action of the latch ring A upon the inclosed series of knitting needle latches. 30 and the general purpose of providing for

closure of the thread guide gap C therein. are well understood. My improved means for effecting such closure comprises primarily a novel form and arrangement of the gap-closing device; and secondarily for the 60 operation of said device by one of the pivoted members which are arranged to swing into and out of the gap C, and more particularly by that one of said members which serves as a carrier for the high-splice 65 thread commonly employed. This operating member as represented is a special form of high splice thread carrier such as is set forth in my Patent 1,291,155, dated Jan. 14, 1919, but such special form is not essential 70 to the present invention which contemplates even the employment of a similarly pivoted non-thread carrying member as a special operating member; but the employment of the high-splice thread carrier member for 75 such purpose is preferred, because I have found it may be so used simply and satisfactorily inasmuch as it is normally raised out of action during reciprocating knitting, at which times only there is such danger of 80 flirting the needle latches as calls for the closing of the gap C to prevent breakage.

My improved gap-closing means comprises, as shown, a combined lever E and gap-closing bar D, mounted on a pivotal 85 support e in a latch ring bracket a which overhangs the gap C; and a movable member B especially adapted to operate said combined lever and bar incidentally with the thread-controlling movement thereof; the 90 gap-closing bar D being approximately arc-shaped around the pivot point e as shown, and being adapted to swing in a slot a¹ provided in the latch ring, and across the gap C from one side thereof toward the other, 95 as indicated by the dotted position D, when the lever portion E is operated by said movable member B.

The gap-closing bar D is normally swung to retracted position by means of a suitable 100 light spring f so as to leave the gap C open; said spring being indicated as wound around the pivotal support e with its extending ends connected respectively to the pivoted lever E and the fixed bracket a. The movable member B which I show as adapted to swing it across the gap to dotted position D, is preferably the one used to carry the usual high-splice thread into or out of operating position in the gap C; and the lever 110

F contacting therewith may be operated by a cam such as it is commonly employed to properly position such thread; though in practice I find it advantageous to provide 5 such cam with an additional step whereby the member B may be raised sufficiently only to throw its thread out of action and permit required adjustment of the other carriers, preliminary to being raised fully to 10 operate the gap-closing device. The bar D, when swung into gap-closing position, passes under the raised members and over the lowered ones.

A yielding contact is preferably provided 15 for between the yarn guide B and the lever portion E of the gap-closing device, by securing a relatively strong spring *b* to the body of the thread guide, so that the free end of said spring will contact with the lever 20 and overcome the tension of the lighter spring *f* which serves to normally retract the bar D; the action being thus made desirably smooth. The improved attachment is very simple and satisfactory in construction, application and operation. 25

What I claim is:

1. In a knitting machine the combination with a plurality of pivotally operated members and a latch ring having a thread-guide 30 gap, of a single gap-closing arc-bar mounted on said ring above said gap, and means for automatically swinging said bar across the whole gap.

2. In a knitting machine the combination 35 with a plurality of pivotally operated members and a latch ring having a thread-guide gap, of a gap closing device pivotally mounted on said ring above said gap and provided with a spring for normally swing- 40 ing it to retracted position; and means for automatically swinging it to gap-closing position.

3. In a knitting machine the combination 45 with a plurality of pivotally operated members and a latch ring having a thread-guide gap, of a gap-closing device pivotally mounted on said ring above said gap, one of said members being adapted to contact with said device so as to swing it across the gap.

50 4. In a knitting machine the combination with a plurality of pivotally operated mem-

bers and a latch ring having a thread-guide gap, of a gap-closing device pivotally mounted on said ring above said gap and provided with a spring for normally swing- 55 ing it to retracted position; one of said movable members being arranged to engage and swing it to gap-closing position.

5. In a knitting machine the combination 60 with a plurality of pivotally operated members and a latch ring having a thread-guide gap, of a gap-closing device pivotally mounted on said ring above said gap and provided with a spring for normally swing- 65 ing it to retracted position; one of said movable members having a spring attachment arranged to yieldingly engage said spring retracted device and swing it to gap- closing position.

6. In a knitting machine the combination 70 with a plurality of pivotally operated members and a latch ring having a thread-guide gap, of a single gap-closing arc-bar pivotally mounted on said ring above said gap, 75 one of said members being adapted to contact with said bar, and the latter being adapted to swing across the whole gap under said contacting member and above the lowered members.

7. In a knitting machine the combination 80 with a plurality of pivotally operated members and a latch ring having a thread-guide gap, of a gap-closing device comprising a lever portion pivoted to said ring above said gap and a gap-closing arc-bar, and a spring 85 for normally retracting said bar; one of said movable members carrying a stronger spring adapted to contact with said lever and swing said bar across the gap, substantially as set forth. 90

8. In a knitting machine the combination 95 with a plurality of pivotally operated members comprising a high-splice thread guide member, and a latch ring having a thread- guide gap, of a gap-closing device pivotally mounted on said ring above said gap and operatively engaged by said high-splice thread guide member so as to throw it into gap-closing position.

In testimony whereof I affix my signature. 100

FRANK W. ROBINSON.
